US0D1025156S

(12) **United States Design Patent** (10) **Patent No.:** **US D1,025,156 S**
(45) **Date of Patent:** **** Apr. 30, 2024**

(54) **VACUUM SEALING MACHINE**

(71) Applicant: **Yulin Fang**, Shenzhen (CN)

(72) Inventor: **Xuefeng Zhang**, Shenzhen (CN)

(73) Assignee: **Yulin Fang**, Shenzhen (CN)

(**) Term: **15 Years**

(21) Appl. No.: **29/921,678**

(22) Filed: **Dec. 19, 2023**

(30) **Foreign Application Priority Data**

Nov. 15, 2023 (CN) 202330746969.3

CLAIM

The ornamental design for a vacuum sealing machine, as shown and described.

DESCRIPTION

FIG. 1 is a front perspective view of a vacuum sealing machine, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the vacuum sealing machine in a state of use; and,

FIG. 10 is a perspective view showing the vacuum sealing machine in an alternate state of use.

The broken lines in the drawings illustrate the portions of the vacuum sealing machine, which form no part of the claimed design.

1 Claim, 10 Drawing Sheets
